(57) **CLAIM**

The ornamental design for a loudspeaker with top-mounted accessory tray, as shown and described.

DESCRIPTION

FIG. 1 is a front, top, right perspective view of a loudspeaker assembly with top-mounted accessory tray according to the present invention;

FIG. 2 is a rear, top, right perspective view thereof;

FIG. 3 is a right side elevation side view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom view thereof.

The broken lines illustrate portions of the loudspeaker assembly with top-mounted accessory tray that form no part of the claimed design.

1 Claim, 8 Drawing Sheets
